US0D1108565S

(12) **United States Design Patent** (10) **Patent No.:** **US D1,108,565 S**
(45) **Date of Patent:** **** Jan. 6, 2026**

(54) **HIP THRUST BELT**

(71) Applicant: **Believe Pursue LLC**, Los Angeles, CA (US)

(72) Inventors: **Brett Andrew Beck**, Los Angeles, CA (US); **Hanna-Greta Kirber Beck**, Los Angeles, CA (US); **Eric Peterson**, Madison, WI (US); **Wang Pai Sheng**, Taiwan (CN)

(73) Assignee: **BELIEVE PURSUE LLC**, Los Angeles, CA (US)

(**) Term: **15 Years**

(21) Appl. No.: **29/934,356**

(22) Filed: **Mar. 25, 2024**

(51) LOC (15) Cl. **21-02**

(52) U.S. Cl.

USPC **D21/662**

(58) **Field of Classification Search**

USPC D21/662-663, 675, 680, 683, 693;
D24/190

CPC A63B 21/00; A63B 21/065

(74) Attorney, Agent, or Firm — Cislo & Thomas, LLP

(57) **CLAIM**

The ornamental design for a hip thrust belt, as shown and described.

DESCRIPTION

FIG. 1 is a front perspective view of a first embodiment of our hip thrust belt design;

FIG. 2 is a rear perspective view thereof;

FIG. 3 is a top plan view thereof; and

FIG. 4 is a bottom plan view thereof;

FIG. 5 is a front elevation view thereof;

FIG. 6 is a rear elevation view thereof;

FIG. 7 is a right-side elevation view thereof; and

FIG. 8 is a left-side elevation view thereof.

FIG. 9 is a front perspective view of a second embodiment of our hip thrust belt design;

FIG. 10 is a top plan view thereof;

FIG. 11 is a bottom plan view thereof;

FIG. 12 is a front elevation view thereof;

FIG. 13 is a rear elevation view thereof;

FIG. 14 is a right-side elevation view thereof; and,

FIG. 15 is a left-side elevation view thereof.

The broken lines shown in the drawings depict stitching and form no part of the claimed design.

1 Claim, 9 Drawing Sheets
